UNITED STATES PATENT OFFICE.

JOHN C. KOPE, OF BELLEVUE, PENNSYLVANIA, ASSIGNOR TO THE DUFF MANUFACTURING COMPANY, OF PITTSBURGH, PENNSYLVANIA, A CORPORATION OF PENNSYLVANIA.

RATCHET-JACK.

1,339,377.

Specification of Letters Patent.

Patented May 4, 1920.

Application filed November 4, 1919. Serial No. 325,609.

To all whom it may concern:

Be it known that I, JOHN C. KOPP, a citizen of the United States, and resident of the borough of Bellevue, in the county of 5 Allegheny and State of Pennsylvania, have invented a new and useful Ratchet-Jack, of which the following is a specification.

The invention is an improvement in ratchet-jacks, that is to say, jacks having 10 ratchet teeth on their sliding bars, and pivoted holding and lifting pawls, the latter moved by the operating lever, and reversing means whereby the action of the pawls can be changed from that of raising 15 to that of lowering, and vice-versa. The particular type of ratchet mechanism upon and within which the present invention is an improvement is disclosed in the Hindman Patent 1,093,269 of April 14, 1914, 20 wherein a single spring forms a connection between the pawls, acting as a floating spring, alternately in compression and tension, for lowering, and in sections for raising, at which time its middle region is engaged by the reversing device as a fixed 25 abutment so that the two sections then act similarly and substantially independently to press the pawls constantly toward the rack. In the particular construction illustrated in 30 that patent the spring is a resilient band formed with two outwardly extending loops adjacent the pawl pins and with a central inwardly extending loop, the spring thus comprising a species of zig-zag or W exhibiting narrow bends and distinct lobes, the purpose of which was to secure the necessary stretch and contraction in the different operations. The central loop also served to coöperate with the reversing 35 means, which comprised two parts, a secondary lever pivoted below the spring and having a finger movable forwardly and rearwardly into and out of the loop, and a reversing and locking hand lever having a 40 nose in camming relation to the secondary lever and adapted to seat in a holding notch therein. In practice it was found that still more elasticity could be obtained by making the spring of round wire instead of flat 45 material, coiling the back of the bottom loop in a plurality of convolutions. While the mechanism was effective and of admirable simplicity, it developed that in time the set of the spring was likely to alter, after which 50 the pawls would not act properly for lowering

ing and it was necessary to replace the spring. This will be understood when it is considered that the spring if too long in its rest condition will not be stretched sufficiently on the upstroke of the handle to 60 draw the lifting dog clear of the ratchet tooth when the bar has settled onto the holding dog; while if the spring be a little too short it will not be compressed enough on the downstroke of the lever to move and 65 keep the holding pawl out of engagement while the lifting pawl takes hold again and, after first slightly raising the bar, starts to lower it another step. In the first case the bar will be simply oscillated up and down in 70 place, the lifting pawl continuing to act on the same tooth; in the other case the lifting pawl will move idly up and down the bar, the holding pawl always catching under one tooth. Difficulty was also encountered with 75 the springs breaking, due, I believe, to localization of bending strain, to a lesser aptitude of the narrow loops for opening than for closing, and to crystallization at the end of the central loops where it worked against 80 the finger of the reversing mechanism in raising.

I find that a much more durable and efficient spring can be produced by returning to the band style with a different configuration, combined with which I also provide a simpler reversing means consisting of a reversing and locking hand lever coöoperative directly with the single spring. Said spring is in the nature of an open bow, having a 85 substantially plain or continuous back, with, preferably, a shallow holding notch at the middle, for coöperation with the nose of the reversing lever. Such a spring avoids the sharp bends and narrow loops of the other forms, is unitary rather than subdivided, and its action is more distributed, whereby it is less likely to lose its set or become broken, and at the same time it has ample capacity for flexing, to pull and push upon 90 its moving abutments. In addition, its full back is adapted for coaction with a single reversing lever, the pivotal axis of which is behind the spring, in order that its nose may operate thereon with a wiping or camming 95 action, to be locked at the approximately perpendicular position where it snaps into the notch.

In the accompanying drawings, forming 100 a part hereof:

Figure 1 is a side elevation of the jack, with the side cover removed, and the mechanism in condition for raising; and

Figs. 2 and 3 are schematic side views of the mechanism, illustrating different stages of the lowering operation, the reversing lever being in its idle position.

The jack stand 2 and its base 3 may be made in two halves, united by rivets 40 passing through marginal flanges 24, 28, 30 and 32. The rack-bar 41 is provided on its inner edge with downwardly facing ratchet teeth 42, and has a head 43, and if desired an external toe-lift bar 44 notched at 44^a to support an adjustable toe-lift 46.

The pawl mechanism is contained within a pawl chamber 6 at the back of the stand, said chamber having a window 7 for access. A cover, not shown, is applied over the open side of the pawl case and is secured by screws to the openings 8 and 9.

The operating lever or rocker 49, socketed for the reception of a removable handle, is fulcrumed in the pawl chamber on a rivet 39. Pivoted on its forward end at 50, closely adjacent the rack, is the lifting pawl 51. The holding pawl 52 is pivotied on a rivet 38, higher up and further away from the rack, in overlapping relation to the lifting pawl, the holding pawl thus being mounted on a fixed axis, while the lifting pawl is movable up and down between the holding pawl and the rack. At their intermediate portions, and somewhat nearer their free ends than their pivotal ends, the pawls bear studs or pins 53 and 54, which project outward from the pawl chamber, through the window 7, into the cover chamber 12, at the opposite side of the wall 6. Here their ends are appropriately reduced to receive the curled ends of a spring 56, the spring being held in place by cotter-pins 57 passed through transverse openings in the ends of the studs.

Said spring is made of band or strip material, and has a special conformation, which may be described generally as an open bow. Its back 58 is offset rearwardly from its ends by curves 59, 60 and is substantially full or continuous, as distinguished from the angled or subdivided form of the patent referred to. At its approximate middle there is preferably a shallow, curved holding notch 61. As best constructed, the spring rises from the inner side of the upper terminal eye, and arches rearward over the stud 54, forming the curve 60, thence extends substantially straight downward, forming the back, then swings under and forward in the broader curve 59, and is curled over and around the stud 53.

A single reversing and locking lever 62 is pivoted on the fixed stud 15, which is located behind the spring, and is held in place by a cotter-pin 63. The rear portion of this

lever constitutes a handle, passing outward through a slot in the back of the cover 11, and its short forward arm or nose 64 is formed to ride upon the back of the spring, and to snap, in the perpendicular position, 70 into the notch 61, wherewith it forms an impositive lock.

In this condition, which is the lifting condition, the spring is held or pressed at the middle, so that its upper and lower portions, 75 acting independently, cause both pawls to seek the ratchet at all times. During such operation there is ample accommodation in the broad lower curve 59 for the up and down movements of the lifting pawl, this 80 part of the spring rolling back and forth in a manner best calculated to preserve its original elasticity. The upper part of the spring has only to yield to the slight movement of the holding pawl, which at its tip 85 is only the width of a ratchet tooth face, and at the stud 54 considerably less; and this flexing is distributed between the arch 60, which slightly opens and closes, and the upper part of the back portion. At the 90 middle of the spring, where the shallow curved notch bears on the rounded nose of the reversing lever there is no destructive or fatiguing action.

For lowering, the handle portion of the 95 reversing lever is pushed downward, freeing its nose from the notch, and disposing it clear of the spring, as seen in Figs. 3 and 4. The spring is now floating, and acts as a unit, first in compression and then in tension, according to the positions of the pawls. The general operation is the same as in the Hindman patent aforesaid. On the upper stroke of the handle, the ratchet bar is lowered a tooth by the lifting dog, and during 100 this movement the tensioning of the spring pulls the holding dog beneath a ratchet tooth one higher than it engaged previously. When the rack settles full upon the holding dog, the lifting dog is relieved of its load, 110 and the spring still under tension pulls it out. On the succeeding downstroke of the lever, the lifting dog is pushed upward free of the rack, thereby compressing the spring, which causes it to move inward beneath the 115 next tooth above. Further movement raises the rack slightly, and the lifting pawl is freed and pushed out by the spring. As the timing of the pawls is governed wholly by the spring and the leeway in either direction is inconsiderable, the spring will function properly only so long as its elasticity remains substantially unchanged, and this the present invention aims to secure for the maximum period, as well as guarding 120 against breakage, as heretofore stated. With the spring constructed as described, it will be perceived that the strains in the lowering operation are comparatively mild, and are not concentrated at any point of weak- 125 130

ness but are well distributed. A cam 65 on the inner side of the holding pawl serves to assist the spring in guiding the lifting pawl to its proper engagement with the ratchet, 5 and its presence also compels the disengagement of the holding pawl, if there should be any reluctance in its movement. The rearward movement of this pawl is limited by a fixed shoulder 66 in the back of the pawl 10 case.

What I claim as new is:

1. A ratchet-jack mechanism of the type comprising a lifting pawl, a holding pawl, a single band spring connecting said pawls 15 acting alternately in tension and compression in lowering, and reversing means adapted to bear upon the approximate middle of the back of the spring for raising, characterized by said spring being an open bow 20 with the intermediate portion of its back rearwardly disposed for coöperation with the reversing means.

2. In a ratchet-jack, the combination with a holding pawl and a lifting pawl, of a single band spring connected at its ends to said pawls and bowed rearwardly with a substantially continuous back, and a reversing 25

hand lever having its pivot behind the intermediate portion of the back and its nose arranged for direct camming action thereon. 30

3. The combination with a ratchet-bar, a holding pawl, and an operating lever with a lifting pawl pivoted thereon, of a single spring connecting said pawls acting alternately in compression and tension for lowering, and a reversing and locking hand lever operative directly on said spring. 35

4. In a ratchet-jack mechanism comprising holding and lifting pawls, an open curved band spring connected at its ends to the pawls with a shallow holding notch in its back, and a reversing and holding lever pivoted behind the spring. 40

5. In a ratchet-jack mechanism having holding and lifting pawls with pins, and a reversing lever, a single band spring connected at its ends with said pawls and presenting its back to said reversing lever, said spring having its ends curled around said pins, upper and lower portions curved rearward away from the pins, the lower curve being relatively wide, and a substantially continuous back. 45 50

JOHN C. KOPF.
